UNITED STATES PATENT OFFICE.

GEORGE F. BISCHOF, OF ROCHESTER, PENNSYLVANIA.

BIFUEL CARBURETER.

1,085,239.

Specification of Letters Patent.

Patented Jan. 27, 1914.

Application filed October 26, 1912. Serial No. 727,995.

To all whom it may concern:

Be it known that I, GEORGE F. BISCHOF, a citizen of the United States, residing at Rochester, in the county of Beaver and State 5 of Pennsylvania, have invented certain new and useful Improvements in Bifuel Carbureters, of which the following is a specification, reference being had to the accompanying drawings.

10 The present invention relates to new and useful improvements in bi-fuel carbureters, and has for its primary object to provide a carbureter which permits the utilization of both gasoline and kerosene and also provides 15 means whereby the fuels will be thoroughly mixed with the air or vaporized before directing the same to the cylinders.

Another object of the invention resides in the provision of the air passages with 20 which the outlet ports of the fuel supply chambers directly communicate whereby the oil is carried in suspension by the air and discharged in a finely divided state from the spraying nozzles within the carbureting 25 chamber, and additional suction controlled valves mounted in the wall of said chamber whereby the supply of air to said chamber is automatically increased proportionately to the increase in the fuel supply as the speed 30 of the engine increases, thus insuring a thorough admixture of the air and fuel in proper proportions so that the fuel will be completely vaporized prior to its entrance into the explosion chambers of the engine cylinders.

35 A further object of the present invention is to provide means for regulating the flow of the fuel to the carbureting chamber whereby the operator may when starting 40 the engine use gasoline and when increasing the speed of the engine the kerosene may be admitted to the carbureting chamber in proportions decided by the respective areas of the two nozzles.

45 Further objects will be readily apparent hereinafter as the description continues.

With the above and other objects in view the invention consists of the novel details of construction, combination, formation and 50 arrangement of parts as will be hereinafter more fully described, claimed and particularly pointed out in the accompanying drawings in which—

55 Figure 1 is a plan view embodying my invention, Fig. 2 is a vertical horizontal section of the same, Fig. 3 is a detail horizontal

section. Fig. 4 is a detail section of one of the additional air supply valves mounted upon the casing of the carbureter. Fig. 5 is a side elevation of the lower end portion 60 of the casing or cylinder of the carbureter.

Reference now being had to the accompanying drawings wherein like and corresponding parts are designated by similar reference characters throughout the several 65 views the numeral 1 indicates a tubular casing having a carbureting chamber 2 formed therein in which is pivotally mounted the usual butterfly throttle valve 3. The upper extremity of the casing 1 is provided with 70 an annular flange 4 whereby the same may be detachably secured to the intake manifold of an internal combustion engine.

Secured upon the diametrically opposite sides of the casing 1 and in communication 75 therewith are a pair of storage tanks A and B for the reception of the kerosene and gasoline respectively. The gasoline supply tank comprises a cylindrical casing 5 having formed therein a chamber 6 for the recep- 80 tion of the gasoline and the upper end of the chamber is adapted to be closed by means of a cover 7. Leading to the chamber 6 is a main inlet port 8 being in communication with a suitable supply of gasoline and 85 mounted within the chamber 6 is a float 9 being operatively connected to a needle valve 11 by means of a lever 10 whereby the flow of gasoline to the chamber will be regulated in the usual manner.

90 The kerosene supply tank A is of substantially the same construction as that of the gasoline supply chamber B and therefore a detail description of the same is deemed unnecessary. Extending down one 95 side of each of the chambers of the gasoline and kerosene supply tanks and then diametrically across the bottom thereof are air inlet tubes 12. One end of each of these tubes is threaded as at 13 and adapted 100 to be secured to the opposite sides of the casing 1 and in communication with the carbureting chamber. Formed within the bottom of each of the supply chambers is an opening 14 which is adapted to permit the 105 fuel to flow from the chambers into the tubes 12 and the said tubes each are provided with an adjustable needle valve 15 whereby the flow of fuel from the chambers may be controlled. These tubes each are 110 also provided with a removable plug 16 whereby the sediment or foreign matter col-

lecting within the tubes may be easily and readily cleaned therefrom. Adjustably mounted within each of the tubes 12 are L-shaped spraying nozzles 17 and 17' whereby 5 the gasoline and kerosene respectively may be discharged within the mixing chamber 2.

It is obvious from the foregoing that when the fuel from the chambers is directed to the spraying nozzles the same will be mixed 10 with a suitable supply of air coming through the tubes 12 so that the air will strike the fuel entering from the respective supply chambers through the orifices 14 into the passages 12 and carry the same in suspension 15 to the spraying nozzles from which the same is discharged in a finely comminuted state into the carbureting chamber.

Adjustably mounted within the lower extremity of the casing 1 is a threaded plug 18 20 having formed therein adjacent its marginal edges a plurality of segmental slots 19. These slots 19 permit the flow of air into the mixing chamber but are adapted to be controlled, by a valve plate 20 rotatably 25 mounted upon the plug 18 within the casing 1 and having openings 21 formed therein which are adapted to register with the openings 19. The medial portion of this plug 18 is provided with an opening 18' which is 30 adapted to be automatically closed by means of a spring 22 which normally holds the valve plate 20 in engagement with the upper face of the plug 18. Upon the increased speed of the engine the suction caused within 35 the chamber 2 will cause the valve 20 to open and thereby allow a larger quantity of air to enter the chamber 2.

The plate 20 is provided upon its periphery with a suitable handle 20' which is 40 disposed through an opening 28 in the wall of the casing 1. Spaced tongues 29 are formed upon the lower edge of this opening, the extremities of said tongues being spaced from the upper edge of said opening 45 so that the upper portion of the opening 28 constitutes a circumferential slot 30. The handle 20' is normally disposed between the lower ends of adjacent tongues 29 so as to prevent angular movement of the valve 50 plate from its adjusted position. This plate may, however, be readily lifted by suction from its seat by action of the spring 22, as above explained. The opening 28 in the casing is substantially equivalent in length 55 to the length of the segmental ports 19, and in order to prevent admission of air into the carbureter chamber through this opening when the valve plate is lifted from its seat, I provide a curved upstanding plate 31 60 which is secured to the periphery of the valve plate 20 and has close frictional en-

gagement with the inner surface of the valve casing 1 over the opening 28. It will thus be apparent that when the valve is disposed upon its seat, air cannot enter through said opening. An additional intake port is carried by the casing 1 and in communication with the chamber 2. This intake port 23 is provided with a spring actuated valve 24 whereby upon the increased speed of the engine a larger quantity of air may enter the carbureting chamber 2.

To provide means for regulating the flow of fuel from the chambers to the auxiliary air inlet ports I secure upon the lower extremities of the needle valves beveled gears 25 which are in mesh with beveled gears 26 carried by controlling shafts 27. These controlling shafts 27 are in the available use of the operator whereby the valves may be 80 singly or jointly operated to permit the gasoline and kerosene to be directed to the carbureting chamber of the carbureter.

While from the above I have described and shown the specific embodiment of the present invention it is of course to be understood that other minor details as to changes, formation, alteration and modification may be resorted to that come within the scope of the present invention without departing from the spirit thereof or sacrificing the efficiency of the same.

What I claim is:

In a carbureter, a casing provided with a carbureting chamber, fuel supply tanks each 95 provided with an air passage opening at one of its ends into the carbureting chamber, valves located in the respective passages to control the supply of fuel thereto, spraying nozzles located within the carbureting chamber and connected to the respective passages, a valve removably mounted in one end of said casing to supply air at all times to the carbureting chamber, said valve including a suction controlled adjustable valve plate 100 whereby the normal supply of air to the carbureting chamber may be regulated, an increase in the speed of the engine lifting the valve plate from its seat by suction to increase the supply of air to the chamber, 110 and an additional suction controlled valve mounted in the wall of said casing and automatically opened upon a further increase of the engine speed to supply additional air to the carbureting chamber.

In testimony whereof I hereunto affix my signature in the presence of two witnesses.

GEORGE F. BISCHOF.
